FOLDING FURNITURE LEG

William M. Boenning, Manitowoc, Wis.

Application September 18, 1933, Serial No. 689,843

5 Claims. (Cl. 45—11)

This invention appertains to folding legs for furniture and more particularly to a novel brace and lock for the swinging legs of card and like tables.

8 One of the primary objects of my invention is to provide novel means for securely holding the swinging leg of a table or like piece of furniture in its set-up operative position against accidental swinging movement, said means being quickly removable by an operator, when it is desired to fold the table for storage purposes.

Another salient object of my invention is the provision of a swinging brace for the folding legs of card tables, the brace being provided with a 15 longitudinally extending keyhole slot for receiving the headed guide pin carried by the table leg, the opening of the slot receiving the guide pin when the leg is in its extended operative position, the brace being split at one end to form in conjunction with the slot resilient arms, whereby to facilitate the movement of the guide pin into and out of the opening in said slot incident to the swinging of the leg to its extended and folded positions.

25 A further important object of my invention is the provision of novel means for forming the walls of the keyhole slot adjacent to the opening of said slot, whereby the resilient arms of the brace will be easily sprung apart to facilitate the movement of the guide pin into the opening of the slot, a sliding lock loop being provided for movement over said resilient arms, whereby inadvertent springing movement of the arms will be prevented, so that the leg will be positively held 35 in its extended set-up position.

A further object of my invention is the provision of a novel fixture for connecting the swinging legs of a card table with the top thereof, the fixture embodying right angularly extending 40 braces for the leg, whereby the leg will be thoroughly braced and held against wobbling.

A still further object of my invention is to provide a novel table brace and lock of the above character, which will be durable and efficient in 45 use, one that will be simple and easy to manufacture and one which can be incorporated with a card table at a small cost.

With these and other objects in view, the invention consists in the novel construction, arrangement and formation of parts, as will be hereinafter more specifically described, claimed and illustrated in the accompanying drawing, in which:—

55 Figure 1 is a fragmentary side elevation of a card table showing one corner thereof and illus-

trating my improved brace and lock incorporated therewith, one of the side rails of the table being shown broken away to illustrate structural details.

Figure 2 is a detail vertical section taken on the line 2—2 of Figure 1, looking in the direction of the arrows.

Figure 3 is a horizontal section taken on the line 3—3 of Figure 2, looking in the direction of the arrows.

Figure 4 is a detail vertical section illustrating a slightly modified form of the leg fixture.

Figure 5 is a horizontal section taken on the line 5—5 of Figure 4, looking in the direction of the arrows, illustrating the modified form of fixture.

Figure 6 is an enlarged fragmentary detail side elevation showing the novel construction of the brace, the view showing the swinging leg just prior to being moved to its fully extended position, the arms of the brace being shown spread apart.

Referring to the drawing in detail, wherein similar reference characters designate the corresponding parts throughout the several views, the letter T generally indicates a card table, which, as shown, includes the table top 10 having the side rails 11 secured thereto. Each corner of the table supports the swinging leg 12 and my invention relates more particularly to the novel means for connecting the leg to the table and for locking the same in its extended operative position.

As shown in Figures 1—3, inclusive, each leg is supported by a U-shaped bracket 15 which embraces the upper end of its leg. The outer end of the U-shaped bracket 15 carries an offset arm 16, which can be secured, such as by means of a screw 17, to one side rail 11. The opposite side of the U-shaped bracket 15 has connected therewith an L-shaped bracket 18. The L-shaped bracket 18 embodies the right angularly extending relatively long leg 19 and the inwardly extending relatively short leg 20. The outer end of the short leg 20 has formed thereon an arm 22, which is secured by means of a fastening element 23 to the other side rail 11 of the table. The long leg 19 of the bracket 18 can be provided with a slot 24 to facilitate the placing of the fastening element 23 in place.

Extending through the brackets 15 and 18 is a pivot 25 and one end of this pivot is preferably enlarged and received within an opening in one side rail 11. This pivot 25 also extends through

the upper end of the leg 12 and the leg is rockably mounted on this pivot for movement toward and away from the table top 10.

One of the important features of the present invention is the provision of the swinging brace and lock strap 26. This brace strap 26 is pivotally mounted at its upper end on a pivot screw 27, which is anchored in the inner face of one side rail 11. It is to be noted that this pivot 27 is arranged in spaced relation to the screw 17 which holds the bracket 15 in position. A spacing washer 28 can be placed on the pivot screw between the brace 26 and the inner face of the rail 11.

15 The brace is provided with a longitudinally extending keyhole slot 29 and the opening 30 of this slot is disposed in close proximity to the lower end of the brace. A diagonal slit 31 is formed in the extreme outer end of the brace 26 and this slit 20 communicates with the opening 30 and divides the brace into a pair of resilient arms 32 and 33. The walls of the keyhole slot adjacent to the opening 30 gradually converge toward said opening as at 34, for a purpose which will be later set forth.

25 The leg 12 at a point spaced from the pivot 25 carries a transversely extending headed guide bolt 35. This bolt extends through the slot 29 and the head thereof rides on the outer face of the brace 26. If desired, a bearing washer 36 can be placed 30 on the guide bolt 35 between the leg 12 and the brace 26.

When the leg 12 is in its folded position, the same lies parallel to the table top 10 and the sliding lock brace or link 26 lies longitudinally of the leg between the leg and the adjacent rail 11. In this position, the guide bolt 35 is disposed adjacent to the inner end of the keyhole slot.

When the leg is swung to its extended operative position, the guide bolt 35 rides in the slot toward the outer end thereof and the circular opening 30 of said slot. As the leg reaches its extreme extended position, the guide bolt 35 rides on the converging walls 34 of the brace or link and forces the resilient arms 32 and 33 of the link or brace 45 apart allowing the guide bolt 35 to snap into the circular opening or portion 30 of said keyhole slot. The leg is now held in its extended position and to prevent accidental movement of the leg, a slide lock loop 37 is provided. This loop is mounted on the brace or link 26 for movement toward and away from the outer end of said brace or link and closely embraces the link or brace. Thus, when the leg is in its extended position and the guide bolt is in the circular opening or portion 30 55 of the keyhole slot, the slide loop 37 is moved down on the brace into engagement with the head. This prevents the forcing apart of the resilient arms 32 and 33 and consequently, the guide bolt 35 cannot move out of the opening 30 and the leg 60 is firmly locked in its extended position.

When it is desired to collapse the leg, the lock loop 37 is slid upwardly on the brace, preferably beyond the slot 29, after which a forcible pull is given to the leg which snaps the guide bolt 35 65 from out of the circular portion 30 of the keyhole slot into the longitudinal portion thereof. This permits the quick collapsing of the leg.

Obviously, this provides a simple and durable form of leg lock which can be easily actuated by 700 the ordinary layman.

In order to brace the table leg at right angles to the lock brace 26, a brace strap 38 can be provided. The lower end of the brace strap 38 is securely mounted on the bolt 35 at the inner end 75 thereof. The upper end of the brace strap 38 is

rockably mounted on a pivot 39 carried by a right angularly extending foot formed on the leg 19 of L-shaped bracket 18. The provision of this brace 38 functions to eliminate undue strain on the pivot 25 and the leg is braced in all directions by the use of the braces 26 and 38. 80

Obviously, the bracket for connecting the leg to the table is open to modifications and in Figures 4 and 5, I have illustrated another form of bracket. This bracket is generally indicated by the reference character 45 and includes the parallel side plates 46 and 47, which are connected together by an integral body plate 48 which is placed into abutting engagement with the inner face of the table top. The plate 46 at one end is provided with a right angularly extending integral arm 49, which is secured to the adjacent side rail of the table by means of a suitable fastening element, such as a screw 50. The plate 47 is provided with an offset leg 51 which is secured to the other side rail of the table, such as by means of a screw 52. 85

A supporting shaft 53 rotatably extends through the plates 46 and 47 and into a bearing opening formed in one side rail of the table. This shaft 53 also extends through the upper end of the leg and is firmly anchored to the table leg for movement therewith. If preferred, a key or lock bolt 54 can be placed through the upper end of the table leg at right angles to the shaft 53, and the shaft can be notched to receive said key or 105 bolt 54, whereby to insure the locking of the leg to the shaft. The inner end of the shaft is extended as at 55 and has riveted or otherwise secured thereto, as at 56, a brace strap 57. This brace strap 57 performs the same function as the 110 brace strap 38 and the lower or outer end of this strap is secured to the table leg. In all other respects, the table, the leg and the fixture are the same as that form of the invention shown in Figures 1-3, inclusive. 115

Changes in details may be made without departing from the spirit or the scope of this invention, but what I claim as new is:—

1. The combination with a table including a top, side rails and a swinging leg, means for connecting the leg to the top, bracing means for the leg comprising a swinging brace strap carried by the table, said brace strap being provided with a longitudinally extending keyhole slot with the circular portion of said slot disposed outermost, a 120 guide pin carried by the table leg slidably mounted in said slot for movement into and out of the circular portion of said slot to hold the leg in an extended position, said brace strap being also provided with a slit extending from the outer end 125 of the strap to the circular portion of the keyhole slot, whereby to provide resilient arms on said strap to facilitate the movement of the guide pin into and out of the circular portion of the keyhole slot. 130

2. The combination with a table including a top, side rails and a swinging leg, means for connecting the leg to the top, bracing means for the leg comprising a swinging brace strap carried by the table, said brace strap being provided with a 140 longitudinally extending keyhole slot with the circular portion of said slot disposed outermost, a guide pin carried by the table leg slidably mounted in said slot for movement into and out of the circular portion of said slot to hold the leg in 145 an extended position, said brace strap being also provided with a slit extending from the outer end of the strap to the circular portion of the keyhole slot, whereby to provide resilient arms on said strap to facilitate the movement of the guide pin. 150

- into and out of the circular portion of the keyhole slot, and releasable means for holding the resilient arms against spreading movement, whereby to prevent inadvertent movement of the guide pin 5 out of the circular portion of said keyhole slot.
3. The combination with a table including top, side rails and a swinging leg, means for connecting the leg to the top, bracing and locking means for the leg comprising a swinging strap brace 10 pivotally carried by the table having a longitudinally extending keyhole slot, the circular portion of said slot being disposed adjacent to the outer end of the link, and a guide pin carried by said leg slidably mounted in the slot into and out of 15 the circular portion thereof, the brace strap being also provided with a slit extending from the outer end thereof into the circular portion of the slot, whereby to divide the brace strap into a pair of resilient arms to facilitate movement of the pin 20 into and out of said circular portion, the walls of the slot adjacent to the circular portion being converged, whereby the pin will spread the arms against their inherent resiliency to permit movement of the pin into the circular portion.
- 25 4. The combination with a table including top, side rails and a swinging leg, means for connecting the leg to the top, bracing and locking means for the leg comprising a swinging strap brace pivotally carried by the table having a longitudinally extending keyhole slot, the circular portion of said slot being disposed adjacent to the outer end of the link, and a guide pin carried by said leg slidably mounted in the slot into and out of 30 the circular portion thereof, the brace strap being also provided with a slit extending from the outer end thereof into the circular portion of the slot, whereby to divide the brace strap into a pair of resilient arms to facilitate movement of the pin 35 into and out of said circular portion, the walls of the slot adjacent to the circular portion being converged, whereby the pin will spread the arms against their inherent resiliency to permit movement of the pin into the circular portion.
- end thereof into the circular portion of the slot, whereby to divide the brace strap into a pair of resilient arms to facilitate movement of the pin into and out of said circular portion, the walls of the slot adjacent to the circular portion being converged, whereby the pin will spread the arms against their inherent resiliency to permit movement of the pin into the circular portion, and releasable means for holding the arms against spreading movement, when the guide pin is in the 80 circular portion of the slot.
5. The combination with a table including top, side rails and a swinging leg, means for connecting the leg to the top, bracing and locking means for the leg comprising a swinging strap brace 85 pivotally carried by the table having a longitudinally extending keyhole slot, the circular portion of said slot being disposed adjacent to the outer end of the link, and a guide pin carried by said leg slidably mounted in the slot into and out of 90 the circular portion thereof, the brace strap being also provided with a slit extending from the outer end thereof into the circular portion of the slot, whereby to divide the brace strap into a pair of resilient arms to facilitate movement of the pin 95 into and out of said circular portion, the walls of the slot adjacent to the circular portion being converged, whereby the pin will spread the arms against their inherent resiliency to permit movement of the pin into the circular portion.
